D. G. KNECHT.
HEADLIGHT GLARE SHIELD,
APPLICATION FILED NOV. 24, 1916.

1,289,814.

Patented Dec. 31, 1918.

UNITED STATES PATENT OFFICE.

DAVID G. KNECHT, OF ALLENTOWN, PENNSYLVANIA.

HEADLIGHT GLARE-SHIELD.

1,289,814.

Specification of Letters Patent. Patented Dec. 31, 1918.

Application filed November 24, 1916. Serial No. 133,242.

To all whom it may concern:

Be it known that I, DAVID G. KNECHT, a citizen of the United States, and a resident of Allentown, in the county of Lehigh and 5 State of Pennsylvania, have invented certain new and useful Improvements in Headlight Glare-Shields, of which the following is a specification.

My invention relates to improvements in 10 glare shields for the headlights of automobiles or other similar vehicles, and it consists in the combinations, constructions and arrangements herein described and claimed.

The object of my invention is to provide 15 a device in which the light is directed downwardly so as to illumine the road, without, however, being diminished in intensity.

A further object of my invention is to provide a device of the type described in which 20 means is provided for preventing the glare which is so dangerous for persons approaching the machine.

Other objects and advantages will appear 25 in the following specification, and the novel features of the invention will be particularly pointed out in the appended claims.

My invention is illustrated in the accompanying drawings, in which:

Figure 1 is a perspective view of the device.

Fig. 2 is a section through the device.

Fig. 3 is a plan view of the device.

Fig. 4 is a front view, and

Fig. 5 is an enlarged section through a 35 portion of the device shown in Fig. 2.

In carrying out my invention I provide a ring 1 of standard size, this ring being L-shaped in cross section, as shown in Fig. 5. Secured to the ring is a series of louvers such 40 as those shown at 2, 3, 4, etc. These louvers are preferably metal plates which are arranged in substantially parallel relation. As will be seen from Fig. 2, in the normal position of the lens plate P, the plates are 45 inclined downwardly from the horizontal, the front end of one plate being substantially level with the rear end of the plate beneath it, or in other words the louvers are inclined to the normal to the lens plate P. 50 The top plate or louver 2 has a substantially flat portion 2^x, a curved portion 2^y on either side thereof, and flat portions 2^z at the sides. The next plate 3 and the remaining plates

extend slightly beyond the ring 1, as shown in Fig. 4, but have reduced portions 9 which 55 are arranged to enter the ring and are secured to it by riveting or any other suitable manner.

In order to hold the louvers in spaced relation, I provide at the sides, brace members 60 10, these brace members having portions which straddle the edges of the louvers, the portion of the brace members between the adjacent louvers being straight. The brace members 10 are soldered or otherwise se- 65 cured to the louvers.

As will be seen from Fig. 2, the upper louver 2 is the longest one, and the lower louver 8 the shortest one. Obviously the device 70 might be built of any other than the number of louvers shown, without departing from the spirit of the invention.

The upper surface of each louver is painted or otherwise made a dead black, with the exception of the top one, the idea being to 75 prevent reflection of light from the upper surface. The under surface of each louver is made reflecting by means of a metallic paint or by polishing the metal, or in any other suitable way.

The ring 1 is made of a standard size, and it is secured to a ring 12 preferably by riveting, as shown in Fig. 5. The rings 12 may be made in various sizes to adapt them to lamps of various sizes. The ring 12 is 85 preferably hinged to the lamp housing H and is provided with locking members L for securely holding the ring 12 to the lamp housing.

From the foregoing description of the various parts of the device, the operation 90 thereof will be readily understood.

The light from the lamp M cannot shine directly ahead, because of the fact that the louvers are in the path of the rays. The 95 rays of light are deflected downwardly in front of the vehicle so that a person approaching the headlight could not be blinded by the light. The volume of light will be substantially the same as that given by the 100 lamp without the deflecting louvers, but the light will be brought into the position where it is most needed and where it cannot cause dangerous collisions due to an unprotected glare.

The locking members L may be unloos-

ened, and the ring 12 with the louvers may be swung on the hinge K so as to permit the cleaning of the lens P.

I claim:

- 5 1. A headlight glare shield comprising a ring hingedly secured to the headlight housing, a plurality of louvers secured to said ring, all of said louvers extending forwardly from the headlight and being inclined down-
wardly, and means for spacing the front ends of the louvers apart and holding them in spaced relation, the front end of each louver being substantially on a horizontal level with the rear end of the louver below it.
- 10 15 2. A headlight glare shield comprising a ring hingedly secured to the headlight housing, a plurality of louvers secured to said ring, all of said louvers extending forwardly from the headlight and being inclined down-
wardly, means for spacing the front ends of the louvers apart and holding them in spaced relation, the front end of each louver being substantially on a horizontal level with the rear end of the louver below it.
- 20

with the rear end of the louver below it, the upper surface of all the louvers except 25 the top one, being black, and each louver having a lower reflecting surface.

3. A headlight glare shield comprising a ring hingedly secured to the headlight housing at the top thereof, a plurality of louvers 30 secured to said ring, said louvers extending forwardly from the headlight and being inclined downwardly, means for spacing the front ends of the louvers apart and for holding them in spaced relation, the 35 front end of each louver being substantially on a horizontal level with the rear end of the louver below it, the upper surface of all of the louvers except the top one, being black, and each louver having a lower reflecting surface, and locking means for holding the ring in position on the housing. 40

DAVID G. KNECHT.
